CONTAINER CLOSURE

Alfred Kachler, Chicago, Ill., assignor to Wilson & Bennett Manufacturing Company, Chicago, Ill., a corporation of Illinois

Application June 20, 1936, Serial No. 86,323

7 Claims. (Cl. 230—61)

My invention is for a barrel or other container of the type known as a full open head in which the head is clamped in closing position by means of a novel ring. Various types of rings of this character have been heretofore used or proposed but many of them were either complicated in construction or unsatisfactory in operation. In accordance with this invention I provide a closing ring having a single moving part or closing lever which is pivoted to one end of the ring and pivotally connected to the other end by means of a 5 slideable or movable pivot.

The objects of the invention are to provide an improved container closure of the character indicated which will be simple and comparatively cheap in construction and durable and efficient and easy in operation.

Other objects and advantages will appear more fully from the following description taken in connection with the accompanying drawing in which

Figure 1 is a top plan view showing a portion of the ring in open position;

Figure 2 is a similar view showing the ring in closed position with parts broken away or shown 25 in section;

Figure 3 is a sectional view taken on the line 3—3 of Figure 2; and

Figure 4 is a sectional view taken on the line 4—4 of Figure 3.

The drum or barrel 6 has a bead or roll 7 around the upper end and is provided with a cover 8 having a depressed portion or wall 9 and a flange 10. The flange 10 extends out over the bead 7 and a gasket 11 is usually interposed therebetween if a tight closure is to be made.

The head is clamped in closing position by means of a split contractible ring 12 which is substantially semi-circular in cross section or having converging engaging walls which coact 40 with the bead and flange as will be readily understood by those familiar with these devices. One end 13 of the ring is provided with a pivot plate or lug 14 which is preferably welded thereto and which extends inwardly to clear the outer wall 45 of the cover and circumferentially a substantial distance beyond the opposite end 15 of the ring. The lug 14 is offset or depressed at 16 so that its outer or free end will clear other operating parts. The opposite end 15 of the ring has an 50 inwardly extending lug or projection 17 which overlies the depressed portion of the lug 14 when the ring is closed as shown particularly in Figures 2 and 3. The operating lever 18 is pivoted at 19 to the end of the lug 14 and the main arm 55 thereof is curved to conform to the curvature of

the barrel and engages with a catch 20 extending inwardly from the ring, to hold the ring closed. The short arm 21 of the lever 18 is preferably bifurcated and straddles the lug 17. The lug 17 has a substantially radial slot 22 which serves 5 as a guideway for a rivet or pivot member 23 which extends through the bifurcated end of the lever. The pivot is preferably provided with a rectangular block or cross-head 24 which fits freely in the slot 22, this block also serving as a 10 spacer or spreader for the ends of the lever.

I have found that the provision of a variable or slideable pivotal connection between the lever and the lug 17 is particularly necessary or desirable in closures of this type in order to facilitate the convenient and easy operation of the same. When the lever 18 is moved to extreme open position as shown in Figure 1, the slide or block 24 will usually be at the inner end of the slot or toward the center of the barrel. In order 20 to limit the opening movement of the handle I provide a stop lug or detent 25 on the end of the ring or forming a part of the lug 17 which engages with the wall 26 at the inner end of the slot in the bifurcated end 21 of the lever 18. This 25 effectually prevents the parts from swinging beyond the desired full open position as shown in Figure 1. As the lever 18 is swung inwardly or towards the center of the barrel during the closing movement the slide 24 moves outwardly or 30 toward the outer end of the slot 22 and remains in this position through the major part of the closing operation. This movement of the slide in the slot prevents undue radial movement of the end 15 of the ring and reduces the power or 35 effort necessary for actuating the same. As the lever reaches the end of its closing movement the block or slide 24 moves inwardly along the slot to its extreme inner position as shown in Figure 2, thus shifting the pivotal point and permitting a powerful final closing action or toggle 40 action which is desirable for drawing the ends together to make a tight closure. The position of the pivot 19 with respect to the pivot 23 in the locking position is preferably such that the 45 former has passed the dead center thereby taking the holding strain off from the lever.

While I have shown a simple and convenient means for shifting the pivotal connection between the ring and the lever it will be obvious 50 that other arrangements of this kind may be utilized without departing from the scope of my invention and other changes may also be desirable in order to adapt the ring for different types of barrels, drums or containers, and therefore I 55

do not wish to have my invention limited to the particular construction herein shown and described except as specified in the following claims, in which I claim:

5. 1. A closing ring of the character set forth having a lug on one end extending inwardly and circumferentially beyond the other end when in closed position, and an inwardly extending lug on the opposite end which overlies the first named lug when in closed position, and a closing lever 10 which has a substantially straight inner end pivoted at the end of the first named lug at a point closely adjacent the inner periphery of the ring with its short end having a movable pivotal connection with the second named lug at a point adjacent the opposite end of the ring and close to the inner periphery thereof whereby the lugs will be moved to overlying position when the ring is closed.
15. 2. A contractible split closing ring of the character set forth having an inwardly extending lug at one end with a substantially straight radial slot therein and having an inwardly and circumferentially extending lug at the opposite end which overlaps the first named lug when in closed position, a closing lever pivoted at the end of the last named lug at a point close to the inner periphery of the ring, said closing lever having a bifurcated end straddling the first named lug, 20 and a pivot connecting the bifurcated ends and extending through said slot, said pivotal points lying on a substantially circumferential line within the periphery of the ring when the ring is in closed position.
25. 3. A split closing ring for containers having a pivot plate at one end which extends a substantial distance beyond the opposite end, a lug on the opposite end overlapping the pivot plate when in closed position, an operating lever pivotally connected with the end of the pivot plate and having one end projecting over said lug, a slide mounted 30 in a substantially radial guideway in said lug and a pivot connecting said slide with the end of the lever, said pivot points lying on a substantially circumferential line within the periphery of the ring and close to the ring when in closed position.
35. 4. A contractible split channel shaped ring for fastening heads on containers, having a circumferential projection within the inner periphery of the ring and extending beyond the end, a curved lever pivotally connected to the end of said projection and having a movable pivotal connection with the other end of the ring, said pivotal connections lying close to the ring when in closed position and lying on a substantially circumferential line within the periphery of the ring, said lever serving to first swing the ends toward each other and finally swing the last named end inwardly to close the same and also serving to spread the ends apart for opening the same.
40. 5. The combination with a metal container having an open end with a bead around the same and a removable cover having a marginal flange 45 overlying the bead, of a contractible clamping ring having portions engageable with the bead and flange for pressing the same together when the ring is contracted, and means for contracting the ring comprising a single curved lever member having a straight end portion at one end substantially in alignment with the adjacent portion and providing a tangential end portion having pivotal connection with one end of the ring, said member also having a slidable pivotal connection 50 with the opposite end of the ring, said last named connection being spaced from the first named connection and also being located at a distance circumferentially from the last named end of the ring, said pivotal connections also lying on a substantially circumferential line within the ring when in closed position, and means on the ring for engagement with said movable member to limit the opening movement thereof.
55. 6. The combination with a container having a removable head, of a split channel shaped ring for fastening the head to the container, said ring having an inwardly extending pivot plate which projects circumferentially beyond the opposite end and which has an offset portion, a lever pivoted to the outer end of the pivot plate and having a bifurcated short end, a lug on the opposite end of the ring extending inwardly through the bifurcated end and having a substantially straight, short radial guideway, a block slidably mounted 60 in said guideway, a pin extending through said block and the bifurcated end, and a detent on the last named end for engagement with the lever to limit the opening movement thereof.
65. 7. A closing ring for containers of the character set forth, comprising a split ring having a circumferential projection on the inside thereof extending a substantial distance beyond one end of the ring and having an inwardly extending projection adjacent to the opposite end thereof, a closing lever having a substantially straight pivotal portion terminating in a curved extension adapted to lie within the periphery of the ring when closed, said straight portion being pivotally connected to the first named projection at a point which is close to the inner periphery of the ring when the ring is closed and having a sliding pivotal connection at the end thereof with the second named projection, said sliding pivot having a limited radial movement in the projection, the arrangement being such that when the ring is in open position said projections will be substantially in alignment and when the lever is swung to close the same the slidable pivot will swing out and over the first named pivot to bring the projections into overlapping relation with the pivots on a substantially circumferential line within the periphery of the ring when in closed position, the final movement serving to force the last named end inwardly toward the center, substantially as described.

ALFRED KAEHLER.
